WALL COPING

James J. Dyer, Steubenville, Ohio

Application July 20, 1940, Serial No. 346,581

12 Claims. (Cl. 72—86)

This invention relates generally to wall coping and more particularly to coping in which the coping sections are provided with a tongue-and-recess construction, whereby the coping sections may be jointed to form smooth tight joints and in which the rain is prevented from entering the interior of the coping.

In the accompanying drawing, which illustrates a preferred embodiment of the invention: Fig. 1 is a plan view of a coping made of coping sections according to the present invention, a portion being broken away;

Fig. 2 is a view taken along the line II—II of Fig. 1, a part being a longitudinal side elevation and a part being a longitudinal vertical section;

Fig. 3 is a transverse vertical section through a brick wall showing a coping section applied thereto;

Fig. 4 is a perspective view of a portion of a coping section showing the tongue end; and

Fig. 5 is a view similar to Fig. 4, showing the recess end of the coping section.

Referring more particularly to the accompanying drawing, the coping is made up of coping sections 2 joined in end to end relation with cement, mortar or the like indicated by the reference numeral 3. Each coping section has an arcuate upper wall 4 and a substantially flat horizontally extending lower wall 5. These walls are spaced apart to provide a recess 6. The coping section has side flanges 7 which connect the upper and lower walls and extend below the lower wall 5, so that the lower portion 8 of the flange lies adjacent to the side of the brick wall 9, as shown in Fig. 3.

A web 10 extends longitudinally of the coping section and connects the upper and lower walls 4 and 5. As shown in Figs. 1 and 5, this web terminates short of the recess end of the coping section, in order to receive a tongue of an adjoining coping section, as will be more particularly described.

As most clearly shown in Fig. 4, each coping section has a tongue indicated generally by the reference numeral 12 formed on one end thereof. This double walled tongue includes an upper arcuate wall 13 and a substantially flat horizontal lower wall 14, which merge at their ends. The tongue 12 extends the full width of the coping section. The end of the coping section opposite the tongue 12 has a notch 15 formed in each of the side flanges 7, in order to receive the ends of the tongue 12. When two coping sections are jointed together, the main portion

of the tongue 12 is received in the recess 6 formed between the upper and lower walls 4 and 5. The ends 16 of the double walled tongue 12 are received in the notches 15. The upper surface 17 of the upper wall 13 of the tongue 12 lies adjacent to and beneath the lower surface of the wall 4. The lower surface 18 of the tongue lies adjacent to and above the upper surface of the lower wall 5.

As shown most clearly in Figs. 3 and 5, the lower surface of the lower wall 5 has longitudinally extending ribs 19 which act to properly seat the coping section and to lock it to the top of the wall 9 by means of the mortar into which the ribs extend. In order to further increase the locking effect, the under surface of the wall 5 and the inner surface of the flanges 7 are provided with small grooves 18.

The double wall construction of the coping section produces a very strong coping which requires less cement for joining it to the brick wall than would be the case if the coping sections were of a single walled construction. The double walled tongue likewise increases the strength of the coping at the joint and, since the tongue 12 extends the full width of the coping, any water which may seep into the joint runs down the outside of the coping rather than on to the brick wall. The coping sections, although securely locked together and to the brick wall, provide a smooth top surface free from unsightly projections.

I have illustrated and described a preferred embodiment of the invention. It is to be understood, however, that the invention may be otherwise embodied within the scope of the following claims.

I claim:

1. A coping section, comprising spaced apart upper and lower walls providing a recess therebetween, side flanges connecting the upper and lower walls and extending below the lower wall, and a tongue on one end of the coping section adapted to be received in the recess between the upper and lower walls of an adjoining coping section when two coping sections are joined together.

2. A coping section, comprising spaced apart upper and lower walls providing a recess therebetween, side flanges connecting the upper and lower walls and extending below the lower wall, and a double walled tongue on one end of the coping section adapted to be received in the recess between the upper and lower walls of an adjoining coping section.

3. A coping section, comprising spaced apart upper and lower walls providing a recess therebetween, side flanges connecting the upper and lower walls and extending below the lower wall, a tongue on one end of the coping section, said tongue extending the full width of the coping section, said side flanges being notched to receive the ends of the tongue, the tongue being adapted to be received in the recess between the upper and lower walls of an adjoining coping section when two coping sections are joined together.
4. A coping section, comprising spaced apart upper and lower walls providing a recess therebetween, side flanges connecting the upper and lower walls and extending below the lower wall, a double walled tongue on one end of the coping section, said tongue extending the full width of the coping section, said side flanges being notched to receive the ends of the tongue whereby the tongue is adapted to be received in the recess between the upper and lower walls of an adjoining coping section.
5. A coping section, comprising spaced apart upper and lower walls providing a recess therebetween, side flanges connecting the upper and lower walls and extending below the lower wall, a web connecting the upper and lower walls located between said flanges, said web terminating short of one end of the coping section, and a tongue on the opposite ends of the coping section adapted to be received in the recess between the upper and lower walls of an adjoining coping section.
6. A coping section, comprising spaced apart upper and lower walls providing a recess therebetween, side flanges connecting the upper and lower walls and extending below the lower wall, a web connecting the upper and lower walls located between said flanges, said web terminating short of one end of the coping section, and a double walled tongue on the opposite end of the coping section adapted to be received in the recess between the upper and lower walls of an adjoining coping section.
7. A coping section, comprising spaced apart upper and lower walls providing a recess therebetween, side flanges connecting the upper and lower walls and extending below the lower wall, a web connecting the upper and lower walls and located between said side flanges, said web terminating short of one end of the coping section, a tongue on the opposite end of the coping section, said tongue extending the full width of the coping section, said side flanges being notched to receive the ends of the tongue whereby the tongue is adapted to be received in the recess between the upper and lower walls of an adjoining coping section.
8. A coping section, comprising spaced apart upper and lower walls providing a recess therebetween, side flanges connecting the upper and lower walls and extending below the lower wall, a web connecting the upper and lower walls and located between said side flanges, said web terminating short of one end of the coping section, a tongue on the opposite end of the coping section, said tongue extending the full width of the coping section, said side flanges being notched to receive the ends of the tongue whereby the tongue is adapted to be received in the recess between the upper and lower walls of an adjoining coping section.
9. A coping section, comprising an arcuate upper wall and a substantially flat lower wall spaced from each other to provide a recess therebetween, side flanges connecting the upper and lower walls and extending below the lower wall, and a tongue on one end of the coping section adapted to be received in the recess between the upper and lower walls of an adjoining coping section.
10. A coping section, comprising an arcuate upper wall and a substantially flat lower wall spaced from each other to provide a recess therebetween, side flanges connecting the upper and lower walls and extending below the lower wall, a double walled tongue on one end of the coping section, said tongue including an arcuate upper wall and a substantially flat lower wall, said tongue adapted to be received in the recess between the upper and lower walls of an adjoining coping section.
11. A coping section, comprising an arcuate upper wall and a substantially flat lower wall spaced from each other to provide a recess therebetween, side flanges connecting the upper and lower walls and extending below the lower wall, a double walled tongue on one end of the coping section, said tongue including an arcuate upper wall and a substantially flat lower wall, said tongue extending the full width of the coping section, said side flanges being notched to receive the ends of the tongue whereby the tongue is adapted to be received in the recess between the upper and lower walls of an adjoining coping section.
12. A coping section, comprising an arcuate upper wall and a substantially flat lower wall spaced from each other to provide a recess therebetween, side flanges connecting the upper and lower walls and extending below the lower wall, a web connecting the upper and lower walls and located between said side flanges, said web terminating short of one end of the coping section, a double walled tongue on the opposite end of the coping section, said tongue including an arcuate upper wall and a substantially flat lower wall, said tongue extending the full width of the coping section, said side flanges being notched to receive the ends of the tongue whereby the tongue is adapted to be received in the recess between the upper and lower walls of an adjoining coping section.
